UNITED STATES PATENT OFFICE

WILLIAM RICHMOND, OF TORONTO, ONTARIO, CANADA

WASHING MACHINE

Application filed February 24, 1930. Serial No. 420,988.

This invention relates to improvements in washing machines of the type in which the clothes are positively moved in a tub by parts having an oscillating rotary movement 5 about a vertical axis. As such machines are at present constructed they are either not as effective as they might be in moving the clothes or else have a tendency to scuff and tear the clothes, and my object is to devise 10 a machine of this type which will effectively move the clothes in the tub without undue wear and tear.

I attain my object by means of a construction which may be briefly described as follows. Within a tube is mounted an agitator comprising a disk located adjacent the bottom of the tub and secured to a sleeve extending upwardly and driven by a drive shaft extending through the bottom of the 20 tub. Up from the disk extend a plurality of cylindrical pins which reach to a point above the upper surface of a wash for which the tub is designed. These pins are preferably positioned about midway between the 25 sleeve and the wall of the tub.

The invention is hereinafter more specifically described and is illustrated in the accompanying drawings in which

Fig. 1 is a vertical section of a washing 30 machine showing only parts relating to my invention; and

Fig. 2 a plan view of the same.

In the drawings like numerals of reference indicate corresponding parts in the different 35 figures.

Referring to the drawings, 1 is a tub formed of metal and shown as supported on the legs 2. Projecting upwardly from the bottom of the tub is a sleeve 3 which 40 extends well above the normal water line of the tub. Through this sleeve extends the driving shaft 4 which will be driven by any suitable means (not shown).

Within the tub is positioned an agitator 45 which comprises the disk 4, the cylindrical sleeve 5 and the upwardly extending pins 6. The sleeve 5 embraces the sleeve 3 and its upper end is squared to receive the squared upper end of the driving shaft 4 which will be given an oscillatory movement

by any suitable mechanism. The disk 4^a, it will be noted, is considerably less in diameter than the wall of the tub 1 and to it, adjacent its rim, are secured the pins 6 which are preferably cylindrical in form and 55 parallel to the axis of the agitator and have their upper ends formed with hemispherical caps 7, of greater diameter than the pins, which prevent injury to the clothes when the latter are being introduced in to the 60 tub. These pins also extend well above the normal water level of the tub when the latter contains a wash of the size for which the machine is adapted with a sufficient 65 margin for any probable higher level. When the clothes are introduced into the tub they lie between the sleeve 5 and the wall 1 of the tub and between and not over the pins 6. The wall of the tub is, of course, smooth and free from projections. Further the 70 positioning of the pins 6 is such that they carry the clothes back and forth without exerting any material outward pressure thereon. The clothes are thus thoroughly agitated and swirled through the water without 75 coming into contact with any projecting pins or surfaces which will cause scuffing or wear, the result being that the clothes are thoroughly cleansed in a shorter period of time than is possible with ordinary constructions.

What I claim as my invention is:

1. In a washing machine the combination of a tub; an agitator mounted therein to revolve on a vertical axis comprising a disk located adjacent the bottom of the tub, a central sleeve extending above the normal water level in the tub, and a plurality of upwardly extending pins carried by the disk 85 parallel to the axis of the agitator and also extending above the normal water level in the tub.

2. In a washing machine the combination of a tub; an agitator mounted therein to 95 revolve on a vertical axis comprising a disk located adjacent the bottom of the tub, a central sleeve extending above the normal water level in the tub, and a plurality of upwardly extending cylindrical pins carried by the disk parallel to the axis of the 100

agitator and also extending above the normal water level in the tub, and hemispherical caps on the pins of greater diameter than the pins.

5 3. A washing machine constructed as set forth in claim 1 in which the pins are located approximately midway between the axis and circumference of the tub.

10 Signed at Toronto, Ont., this 7th day of February, 1930.
